FLIER FOR WRAPPING YARN AROUND
WIRE

Charles J. Murphy, Fort Wayne, Ind., assignor to
Essex Wire Corporation, Fort Wayne, Ind., a
corporation of Michigan

Application June 26, 1943, Serial No. 492,372

1 Claim. (Cl. 57—18)

This invention relates to improvements in fliers for wrapping yarn around wire to provide a covering for insulation or other purposes.

Generally, apparatus used for wrapping yarn around wire includes a basket or cage in which the yarn cop is disposed and more or less concealed from view. Such arrangement necessitates frequent inspection of each unit individually by the operator in order to apprehend exhaustion of the supply of yarn as it is drawn from the cops.

An object of the present invention is to provide a flier so constructed that when a group of similar fliers are arranged to be operated concurrently under management of a single operator, the depletion of the yarn, as it is withdrawn from the various cops, is readily detected by the operator when replenishment with new cops is required.

Another object of the invention is to provide a flier from which yarn is withdrawn from the cop and wrapped around a wire, so constituted as to be fully exposed to observation during operation thereof wherefore to enable the operator to readily ascertain the progress of depletion of the various cops during withdrawal of the yarn therefrom.

Other objects and advantages of the invention appear in the following description.

An illustrative embodiment of the invention is shown in the accompanying drawing, in which:

Fig. 1 is a top plan view of a structure in which the invention is incorporated;

Fig. 2 is a side elevational view projected from Fig. 1, a portion thereof being broken away;

Fig. 3 is a side elevational view of a cop supporting post, a portion thereof being broken away;

Fig. 4 is a top plan view projected from Fig. 3;

Fig. 5 is a top plan view of a friction plate used in the structure;

Fig. 6 is a side elevational view projected from Fig. 5, partially in section; and

Fig. 7 is a plan view of a friction pad forming part of the structure.

The illustrative embodiment of the invention consists of a hollow spindle 8 mounted for rotation upon its axis and driven by any suitable mechanical means (not shown). The spindle has secured concentrically thereon a bed-plate 9 having an upstanding yarn-receiving post 10 the axis of which is disposed parallel with that of the spindle, and an upstanding guide-supporting post 11 to which are secured an intermediate guide-hook 12 and a top guide-hook 13, said posts being

located on said bed-plate at points adjacent each other and near the outer periphery thereof.

In the top of the spindle 8 is secured, by means of a collar 14, a nose piece 15 of a type commonly used on fliers through which the wire 16 passes as it travels upwardly through the bore of the spindle 8. A tubular cop-post 17, provided with radial external ribs 18 and a flange 19 on its lower end, is mounted on said spindle 10 loosely to permit free relative axial and angular movement thereon, the lower end of the post having a recess 20 therein, and a friction disk 21 is firmly secured in the post, there being a sleeve 22 projecting upwardly from the disk that is 15 pressed into the recess.

A circular cushion 23, preferably made of hard felt and provided with a central opening 24, is positioned on the bed-plate 9 and surrounds the spindle, and the friction disk 21 rests upon the cushion so that upon rotation of the bed-plate 20 rotary movement is imparted to the cop-post 17 through the medium of the cushion.

Yarn 25 to be wrapped around the wire 16 is supplied in the form of a cop 26 which is provided with a cop-tube 27, as in the usual manner, the tube being positioned firmly on the post with its inner wall firmly contacting the ribs 18 thereon to insure concurrent rotation of the cop with the 25 post. The cop, its tube-post and friction disk 30 assemblage, when in operating position, rests of its own weight upon the cushion and is rotated together with the spindle, cushion and bed-plate. The arrangement is such as to permit progressive 35 rotation of the friction disk, post and cop relative to the spindle, as the yarn 25 is withdrawn from the cop and wrapped around the wire traveling through the nose piece.

In use, the wire 16 is projected up through the spindle and nose piece, and the free end of the 40 yarn is uncoiled from the cop, strung around the yarn-receiving post, up through the intermediate guide-hook 12 and top guide-hook 13, and around the guide-pin 15 on the nose piece, the extending 45 terminal portion of the yarn then being wrapped manually around the wire preliminary to operating the machine.

The wire is progressed at a predetermined rate 50 of speed upwardly through the spindle and the nose piece by such ordinary means (not shown) as is common in the practice, and concurrently, the spindle together with the bed-plate is rotated by any suitable motion-transmitting mechanism (not shown). Thus, as the wire is progressed the 55 yarn becomes wrapped spirally around the wire

while it is unwound from the cop which accommodately turns together with the post and friction disk under restraint of friction developed between the disk and cushion.

To insure stability of the rotating parts about the axis of the spindle, a weight is secured to the bed-plate consisting of a spindle nut 28 threaded on a stud 29 that projects from the bed-plate together with one or more washers 30 of selected weights, wherefore to counterbalance the weight of the receiving and guid-posts oppositely located on the bed-plate, and to compensate for the drag of the yarn as it is pulled around the receiving post and through the guides into the nose piece.

A feature of the invention is the arrangement by which the frictional resistance to the progressive rotation of the cop and its supporting post is automatically reduced as the load of yarn on the cop diminishes while the yarn is withdrawn therefrom because of the consequent reduction in weight of the cop. By this means the tension of the yarn as it is fed to and wrapped around the wire is substantially constant, resulting in uniformity of the covering of yarn wrapped around the wire.

Variations from the particular construction above disclosed may be resorted to by the exer-

cise of skill in the art, without departure from the spirit or scope of the invention, and the following claim is intended to be inclusive of such variations.

5 What I claim is:

A fier for wrapping yarn around a wire consisting of a rotatable hollow spindle provided with a nose piece on its upper end and a bed-plate rotatable therewith, a cop-post concentrically mounted on the spindle loosely to permit free axial and angular movement relative thereto provided at its lower end with a friction disk, a cushion encompassing the spindle interposed between the bed-plate and disk upon which the assembled cop post, disk and a yarn cop disposed on the cop post rests, and is frictionally engaged thereby, an upright yarn-receiving post on said bed-plate the axis of which is parallel with that of the spindle, an upright guide-supporting post, 20 said yarn receiving and guide-supporting posts being located adjacent each other near the perimeter of said bed-plate, and guides on said supporting post, the arrangement being such as to direct travel of yarn withdrawn from said cop as it is fed to a wire passing up through the spindle and nose piece to be wound thereon.

CHARLES J. MURPHY.
